ALKAMINE ESTERS OF 2-CHLORO-4-AMINO BENZOIC ACID

Henry C. Marks, Glen Ridge, N. J., and Martin I. Rubin, New York, N. Y., assignors to Wallace & Tiernan Products, Inc., a corporation of New Jersey

No Drawing. Application July 21, 1945,
Serial No. 606,476

5 Claims. (Cl. 260—472)

1

The present invention relates to chemical compounds useful in the medical arts and more particularly to local anesthetics.

The various sulfonamide compounds have in recent years come into extensive use in medicine for their bacteriostatic effect in the treatment of a wide variety of infectious diseases and on the basis of extensive clinical use have been found to be valuable therapeutic agents for this purpose. One of the drawbacks to the use of the sulfonamides which has been encountered, however, is their ineffectiveness when employed concurrently with certain of the more widely used local anesthetics. Thus, the various local anesthetics derived from p-aminobenzoic acid, of which procaine (diethylaminoethyl 4-aminobenzoate hydrochloride), commonly known by its trade name "Novocaine," is a well-known example, are specific antagonists for the sulfonamides when present concurrently therewith in the animal body and inhibit the bacteriostatic action of the sulfonamides to such an extent that "Novocaine," for example, cannot safely be used for local anesthesia with a patient who is under sulfonamide therapy.

In those surgical procedures in which local anesthetics are used by methods of continuous perfusion of a body tissue, as in the recently developed caudal anesthesia procedure employed in childbirth, there is a definite risk of infection. It would be desirable to counteract this risk by the addition of a sulfonamide to the anesthetic, but this is not possible when the anesthetic is one of those derived from p-aminobenzoic acid, of which procaine is a widely employed example.

It is an object of the invention to provide compounds which possess good local anesthetic potency, low toxicity, and good solubility, but which at the same time are free from any biotic antagonism to the sulfonamides.

A further object of the invention is to provide compounds of good local anesthetic potency, low toxicity and good solubility which at the same time are bacteriostatic in themselves.

The invention is based on our discovery of certain novel compounds and their effectiveness for the purposes indicated. These compounds are certain monohalogenated derivatives of the amino alcohol esters of p-aminobenzoic acid. The esters of this class when unhalogenated show a significant level of local anesthetic potency and are, because of their low toxicity, water solubility and other properties, suitable for use as local anesthetics except in the presence of the sulfonamide compounds, to which they are

antagonistic and whose bacteriostatic action they inhibit. The monohalogenated derivatives of the present invention not only show an increased anesthetic potency as contrasted with the known monohalogenated and unhalogenated esters but also are compatible with the sulfonamides and do not inhibit their bacteriostatic action. Likewise, in contrast to the monohalogenated amino alcohol esters of p-aminobenzoic acid known to the prior art, and indeed in contrast to certain new monohalogenated amino alcohol esters of p-aminobenzoic acid which we have prepared and describe below, the particular amino alcohol esters of monohalogenated p-aminobenzoic acid of the present invention exhibit, when tested in the usual manner against *E. coli*, a bacteriostatic activity comparable to that of the sulfonamide compounds.

Some of the compounds of the present invention have been found to possess a local anesthetic potency some tenfold greater than procaine. They are less toxic than procaine, showing a toxicity of the order of $\frac{1}{3}$ that of procaine. They, therefore, may be said to have a fifteenfold therapeutic advantage over procaine, disregarding the advantages resulting from their freedom from antagonism to the sulfonamides. The compounds when utilized concurrently with sulfonamide in suppressing the growth of *E. coli* are free from any significant tendency to interfere with the bacteriostatic action of the sulfonamide.

The compounds in the form of their salts are freely soluble in water. They also can be sterilized in aqueous solution by boiling without appreciable hydrolysis of the ester groups present. The compounds are stable and otherwise suitable physically for the use indicated and free from any tendency to produce undesired physiological effects.

The compounds of the present invention comprise the amino alcohol esters of 2-chloro, 3-chloro and 3-fluoro 4-aminobenzoic acids.

Among these esters, we have investigated and found suitable for the purposes of the present invention the beta-diethylaminoethyl, the gamma-diethylaminopropyl, the beta-diethylaminopropyl, the 2-n-aminylamino-2-methyl-1-propyl, the beta-diethylamino-ethoxyethyl, the beta-dimethylaminoethyl, the beta-piperidinoethyl, the beta-(gamma-morpholino) ethyl, the beta-di-n-butylaminoethyl, the gamma-di-n-butylaminopropyl, the 2-n-butylamino-2-methyl-1-propyl, the 2-n-propylamino-2-methyl-1-propyl, and the 2-isopropylamino-2-methyl-1-propyl alcohol

esters of said monohalogenated p-aminobenzoic acids.

The preparation of the compounds of the present invention will be illustrated by a description of the preparation of diethylaminoethyl 2-chloro-4-aminobenzoate hydrochloride. The preparation is carried out in two principal steps.

In the first step, 2-chloro-4-aminobenzoyl chloride-hydrochloride is prepared by refluxing a mixture of 25 cc. of purified thionyl chloride and 10 g. of 2-chloro-4-aminobenzoic acid until all of the solid has gone into solution. To the cooled solution is added 150 cc. of dry ethyl ether. A brisk stream of dry hydrogen chloride is passed into the solution until the precipitation of 2-chloro-4-aminobenzoyl chloride hydrochloride is complete. The acyl halide is removed by filtration and dried in a vacuum desiccator.

In the second step, the diethylaminoethyl 2-chloro-4-aminobenzoate hydrochloride is prepared by refluxing equimolar proportions of the hydrochloride of beta-diethylaminoethanol in a suitable inert solvent such as a mixture of dry toluene and tetrachloroethane and the hydrochloride of 2-chloro-4-aminobenzoyl chloride until the reaction as indicated by the cessation of hydrogen chloride evolution is complete. The supernatant solvents are decanted from the reaction product which can be conveniently purified by crystallization from absolute ethanol. An alternative purification can be effected by dissolving the reaction product in water. The ester base is liberated by rendering the clarified aqueous solution alkaline. Removal of the base from the alkaline solution is achieved by extraction with a suitable solvent such as benzene or ether. The pure hydrochloride of diethylaminoethyl 2-chloro-4-aminobenzoate is then precipitated from the dried extract by the addition of dry hydrogen chloride. After removal by filtration and recrystallization from ethanol it exhibits the following properties: M. P. 173-174° C. Analysis calculated for $C_{13}H_{20}O_2N_2Cl_3$: C, 50.8; H, 6.5. Found: C, 50.9; H, 6.6. The compound is freely soluble in water. Its aqueous solution can be sterilized by boiling without appreciable hydrolysis of the ester.

By utilization of the appropriate acid, in place of the hydrogen chloride cited above, one may prepare the corresponding ester sulfate, phosphate, oxalate, tartrate, malate, succinate, borate, etc.

Of the esters prepared by this general procedure we have found the following compounds, besides the diethyl aminoethyl esters, to be particularly effective for the purposes of this invention:

The gamma-diethylaminopropyl ester hydrochloride of M. P. 197-198° C., analysis calculated for $C_{14}H_{22}O_2N_2Cl_2$: C, 52.4; H, 6.9. Found: C, 52.5; H, 7.0.

The beta-diethylaminopropyl ester dihydrochloride of M. P. 198-199° C., analysis calculated for $C_{14}H_{23}O_2N_2Cl_3$: N, 7.83. Found: N, 7.60.

The 2-n-amylamino-2-methyl-1-propyl ester dihydrochloride of M. P. 202-203° C., analysis calculated for $C_{18}H_{27}O_2N_2Cl_3$: C, 49.8; H, 7.00. Found: C, 50.30; H, 7.14.

The beta-diethylaminoethoxyethyl ester hydrochloride of M. P. 134-135° C.

The beta-dimethylaminoethyl ester dihydrochloride of M. P. 197-198° C., analysis calcu-

lated for $C_{11}H_{17}O_2N_2Cl_3$: C, 41.90; H, 5.40. Found: C, 41.90; H, 5.88.

The beta-piperidinoethyl ester dihydrochloride of M. P. 210.5-211° C., analysis calculated for $C_{14}H_{21}O_2N_2Cl_3$: N, 7.99. Found: N, 7.70.

The beta-(gamma-morpholino) ethyl ester hydrochloride of M. P. 227-228° C., analysis calculated for $C_{13}H_{18}O_3N_2Cl_2$: N, 8.72; Cl, 22.1. Found: N, 8.75; Cl, 22.5.

10 The beta-di-n-butylaminoethyl ester hydrochloride of M. P. 185-186° C., analysis calculated for $C_{17}H_{24}O_2N_2Cl_2$: C, 56.20; H, 7.72. Found: C, 56.32; H, 7.91.

15 The gamma-di-n-butylaminopropyl ester hydrochloride, a hygroscopic solid, analysis calculated for $C_{18}H_{30}O_2N_2Cl_2H_2O$: C, 54.70; H, 7.85. Found: C, 55.33; H, 7.88.

20 The 2-n-butylamino-2-methyl-1-propyl ester dihydrochloride of M. P. 189-190° C., analysis calculated for $C_{15}H_{25}O_2N_2Cl_3$: N, 7.54. Found: N, 7.65.

25 The 2-isoamylamino-2-methyl-1-propyl ester dihydrochloride of M. P. 186-187° C., analysis calculated for $C_{18}H_{27}O_2N_2Cl_3$: N, 7.26. Found: N, 7.35.

30 The diethylaminoethyl ester hydrochloride of 3-chloro-4-aminobenzoic acid of M. P. 149-150° C.

An alternative procedure for the preparation 35 of the type of compounds described above may be illustrated by the preparation of the diethylaminoethyl ester hydrochloride of 3-fluoro-4-aminobenzoic acid:

35 A mixture of 2 g. of 3-fluoro-4-nitrobenzoic acid, prepared as previously described (C. F. Schmelkes and Rubin, J. A. C. S. 66, 1631, 1944), 5 cc. of purified thionyl chloride and 20 cc. of dry benzene was refluxed until the cessation of hydrogen chloride evolution indicated completion

40 of the reaction. The solvents and excess reagents were removed by distillation in vacuo and a solution of diethylamino ethanol in dry benzene was added. After standing overnight the precipitate which had formed was removed by filtration and purified by recrystallization from absolute ethanol. The pale yellow product had a melting point of 190-191° C. On analysis it showed the correct values for the diethylamino-

45 50 ethyl ester hydrochloride of 3-fluoro-4-nitrobenzoic acid. Analysis calculated for $C_{13}H_{18}O_4N_2Cl$: N, 9.00. Found: N, 8.72.

A solution of 1 g. of this product in 135 cc. of absolute ethanol when subjected to the action 55 of hydrogen gas and 0.5 g. of platinum oxide catalyst rapidly absorbed the calculated quantity of hydrogen. The hydrochloride of diethylaminoethyl-3-fluoro-4-amino-benzoate was isolated from the filtered solution by evaporation of the solvent.

60 The diethylaminoethyl 2-chloro-4-aminobenzoate hydrochloride prepared as described above showed, on pharmacological tests on the cornea of the rabbit, a local anesthetic potency approximately ten times that of procaine. The toxicity of the compound as indicated by its M. L. D.₅₀ in mice on intraperitoneal injection in aqueous solution was approximately $\frac{1}{3}$ that of procaine.

65 When tested with *E. coli* in synthetic medium in conjunction with sulfanilamide the diethylaminoethanol ester of 2-chloro-4-aminobenzoic acid in a concentration of 1 mg. % with 50 mg. % of sulfanilamide on incubation for 24 hours at 37° completely inhibited the growth of the organisms. Procaine in 1 mg. % when combined

with sulfanilamide in 50 mg. % under the same test conditions permitted the free growth of the organism. Since the concentration of the diethylaminoethyl ester of 2-chloro-4-aminobenzoic was too low to have of itself inhibited the growth of the organism, this test serves to indicate that the compound is compatible with sulfanilamide in therapeutic usage and, in contrast to procaine, does not inhibit the bacteriostatic action of the sulfonamide.

Diethylaminoethyl-2-chloro-4-aminobenzoate hydrochloride prepared as described above was incubated with liver tissue in simulation of the conditions encountered in the in vivo use of this type of compound. At the end of four hours the mixture was filtered and added to a culture of *E. coli*. After incubation for 24 hours at 37° C. it was revealed that this compound in concentration of 1.5 mg. % had effectively prevented the growth of the organism. Procaine when subjected to an identical test failed to inhibit the growth of the bacteria.

The 3-chloro derivatives and the 3-fluoro derivatives may be prepared in a similar manner using as a starting material the known corresponding halogen-4-aminobenzoic acid.

The properties of the compounds of the present invention of not inhibiting the action of the sulfonamides in conjunction with adequate local anesthetic potency, of being bacteriostatic in themselves, good water solubility and other properties rendering them suitable for clinical use as local anesthetics are quite unexpected in view of the unsuitability of the known corresponding 2 and 3-bromo compounds and the known 2-iodo and 3-iodo compounds.

We have also prepared diethylaminoethyl 2-fluoro-4-aminobenzoate hydrochloride of M. P. 134-135° C. which has not heretofore to our knowledge been prepared or described in the literature. This compound was found to be antagonistic to and inhibitory of the action of the sulfonamides and also to be without inherent bacteriostatic action.

It will be appreciated that the foregoing detailed description of procedures by which the compounds of the present invention may be prepared is made for purposes of illustration and disclosure and that deviations therefrom can be made by those skilled in the art without departure from the principles of the invention. It is intended to cover the novel compounds disclosed irrespective of the process by which they are prepared.

We claim:

1. The 2-chloro-4-aminobenzoic acid esters of the N-alkyl substituted alkyl amino alcohols having less than six carbon atoms and their addition salts.
2. The acid addition salts of the amino alcohol esters of the group claimed in claim 1.
3. Diethylaminoethyl 2-chloro-4-aminobenzoate.
4. The acid addition salts of diethylaminoethyl 2-chloro-4-aminobenzoate.
5. Diethylaminoethyl 2-chloro-4-aminobenzoate hydrochloride.

HENRY C. MARKS.
